The ornamental design for the sole and toe portions of a shoe, as shown and described.

DESCRIPTION

FIG. 1 is a right front perspective view of a sole and toe portions of a shoe showing our new design, the broken line portions of a shoe upper are for illustrative purposes only and form no part of the design;

FIG. 2 is a bottom plan view thereof.

The left side, not shown, is substantially like the right side but without the "tail" which terminates at the rear of the sole.
